COMBINED PHONOGRAPH AND RADIO CABINET

Frank M. Freimann and Clyde L. Welbaum, Fort Wayne,
Ind., assignors to The Magnavox Company, Fort
Wayne, Ind., a corporation

Application March 25, 1957, Serial No. 45,424

Term of patent 14 years

(Cl. D56—4)

The figure is a front perspective view of a combined phonograph and radio cabinet, showing our new design.

The back and side not shown are substantially plain.

We claim:

The ornamental design for a combined phonograph and radio cabinet, substantially as shown and described.
